[57] CLAIM

The ornamental design of a bidet unit for a toilet, as shown.

DESCRIPTION

FIG. 1 is a top perspective view of a bidet unit for a toilet showing my new design;

FIG. 2 is a right side elevational view thereof;

FIG. 3 is a rear elevational view thereof;

FIG. 4 is a left side elevational view thereof;

FIG. 5 is a front elevational view thereof;

FIG. 6 is a top plan view thereof; and,

FIG. 7 is a bottom plan view thereof.

The broken line representation of a toilet seat and toilet seat cover in FIGS. 1 and 7 are for purposes of illustration only and form no part of the claimed design.

FIG. 2

FIG. 3

FIG. 4

FIG. 5

FIG. 6***FIG. 7***
